UNITED STATES PATENT OFFICE.

ANGEL VARGAS, OF ILOILO, PHILIPPINE ISLANDS.

PLOW.

Application filed February 3, 1923. Serial No. 616,674.

To all whom it may concern:

Be it known that I, ANGEL VARGAS, a citizen of the Philippine Islands, residing at Iloilo, Philippine Islands, have invented 5 certain new and useful Improvements in Plows; and I do hereby declare the following to be a full, clear, and exact description of the invention, such as will enable others skilled in the art to which it appertains to make and use the same.

My present invention relates to improvements in plows, and it is intended to provide a cheap, simple, light and efficient plow which may be controlled by a single handle 15 and is of the general type used in certain tropical countries, such as the Philippine Islands.

Such plows are frequently drawn by carabao or water buffalo, and it is desirable to 20 have the clevis at a low height above the ground.

The invention is especially intended to provide a light plow which is capable of either light or heavy work as desired, and 25 which may be conveniently shipped in transit and conveniently used according to tropical standards as described.

My invention is especially intended to provide simplifications of and improvements 30 on the structure shown in my earlier Patent No. 1,020,232, granted March 12, 1912 and entitled Improvements in plows.

My invention will be more fully understood after reference to the accompanying 35 drawings, in which like parts are indicated by similar reference symbols throughout the several views, and in which:—

Figure 1 shows a side elevation of the complete plow, the handle being broken away.

Figure 2 is a plan view of the device shown in Fig. 1.

Figure 3 is a view similar to Fig. 2, but shows the opposite side of the plow, the handle also being broken away.

Figure 4 is a detail showing the means of adjusting the height of the rear end of the plow beam, and incidentally of the clevis, the parts being shown on a larger scale than 50 in the preceding figures, and the parts being broken away.

Figure 5 shows a section along the line 5—5 of Fig. 4, and looking in the direction of the arrows; and

55 Figure 6 shows a section along the line

6—6 of Fig. 3, and looking in the direction of the arrows, the parts being shown on a larger scale than in said figure.

A represents the plow beam which is curved downward at the front and rear. 60 The front end *a* is twisted over to form a horizontal plate to which the clevis B is connected as by means of the bolts C and C'.

D represents the link to which the whiffle tree or other draft apparatus is attached. 65

The rear end of the plow beam is curved downwards as shown at *a'*. Near the upper arched portion of the plow beam the standard E is attached as by means of the bolt F. 70 This standard is concave looking from the

the forward end of the plow. The upper end of the standard is provided with a bracket E' through which the bolt F also passes, which bracket is secured to the standard as by means of the rivets *e'*. The 75 lower end of the standard is bifurcated, as at *e*² and *e*³, and is secured to the landside H by means of the bolts G and nuts *g*, the nuts being mounted beneath the plow share so as not to catch in the dirt. The outer ends 80 of the bolts G are countersunk in the landside as shown in Fig. 3.

At its front end the landside is provided with a flanged portion *h* to which the plow share I is attached. This plow share is connected to the moldboard I' by means of the metal straps K and K', which are riveted as at *k* to the plow share I and are bolted, as at *k'*, to the moldboard I', as shown most clearly in Figs. 1 and 3. 90 The bolts *k'* carry nuts *k*² which are mounted behind the moldboard so as not to engage the dirt. The exposed heads of the rivets *k* and bolts *k'* are countersunk, respectively, in the plow share I and moldboard I', so as 95 to provide a smooth surface.

The moldboard is connected to the standard E by means of the angle brace L. At its rear the landside is provided with an adjustable wear shoe M, which is shown 100 most clearly in Figs. 1 and 3, and this shoe is provided with a groove *m* adapted to engage the lower edge of the landside; and the front edge of this shoe is beveled, as at *m'*, and the bottom edge is straight, as at 105 *m*², so as to provide a wear surface for the rear end of the landside. The landside is provided with a notch or lug *h*², see Figs. 1 and 3, to engage the bevel edge *m'* of the shoe M; said shoe when in the forward po- 110

sition as shown in Figs. 1 and 3 being held in place by the bolt M' and nut m^3 .

The handle bar N is provided at its upper end with a handle n , preferably curved forward, as shown in Figs. 1 and 3, and its lower end is bent substantially at right angles as at n' , and its lower end is secured to the landside by means of the bolts O and O' and the nuts o and o' , as shown most clearly 10 in Fig. 1.

The back of the handle bar rests against the bevel edge m^4 of the shoe M , as shown in Fig. 1. At a suitable height above the shoe M the handle bar is provided with a strap 15 P , see Figs. 3 and 5, which is riveted as at p to the handle bar, and is secured to said handle bar by means of the bolt P' and nut p^2 . The position of the rear end of the plow beam is adjusted inside the strap P by means 20 of suitable wedges Q and Q' which are preferably of wood, and driven into place so as to hold the clevis at the desired height above the ground.

It will be obvious that by driving in one 25 direction on one wedge and driving in another direction on the other wedge, the height of the rear end of the plow beam may be increased or decreased, as desired, and consequently the height of the clevis above 30 the ground may be increased or decreased, as desired.

The rear end of the moldboard is connected to the plow handle by means of the brace R , which brace is connected to the handle bar by means of the bolt P' already described. The brace R is connected at its forward end to the moldboard as by means of the bolts S and nut s , the nut being on the underside of the moldboard, and the head of 40 the bolt being countersunk in the moldboard as shown in Figs. 1 and 2.

It will thus be seen that I provide a cheap, simple and efficient plow which may be easily assembled or taken apart, and from 45 which the parts, such as the plow share, may

be conveniently removed for sharpening, or other repairs, when desired, or from which worn parts may be conveniently removed and fresh parts readily supplied when needed.

It will be noted that the plow is extremely compact in construction, takes up very little room in storage or in shipment, and is of rugged construction especially adapted for the uses hereinbefore stated.

It will be obvious that various changes might be made in the construction, combination and arrangement of parts which could be used without departing from the spirit of my invention; and I do not mean to limit 60 the invention to such details except as particularly pointed out in the claim.

Having thus described my invention what I claim and desire to secure by Letters Patent of the United States is:—

A plow of the character described, comprising a metal beam curved downwards front and rear, a curved standard connected to said beam and bifurcated at its lower end, a landside connected to the bifurcated ends of said standard, the said landside being provided with a laterally projecting flange at the forward edge, a plow share connected to said flange, a moldboard connected to said plow share and to said standard, a single handle bar having its heel bent forwardly at an angle, said bent portion being connected to said landside, a metal strap connected to said handle bar and spaced away therefrom and adapted to receive the rear end of said beam, wedges driven into a space between said strap and said beam for holding said beam firmly in place, a shoe detachably connected to the rear end of said landside and having an inclined edge abutting against said handle bar, and a brace connecting the rear portion of the moldboard with said handle bar.

ANGEL VARGAS.
